UNITED STATES PATENT OFFICE.

FRANK W. MERRICK, OF BOSTON, MASSACHUSETTS.

SEWING MACHINE.

Application filed July 15, 1925. Serial No. 43,685.

The invention is applicable in connection with sewing machines of a well-known general class in which a work-penetrating implement that penetrates the work at the 5 stitch-forming point in a machine, as an incident of stitch-forming operations, has in addition a transverse movement while in the work whereby the work is advanced, i. e., fed. In machines on the order of those to 10 which the invention more particularly is designed to be applied the work is backed up by a work-table or support located immediately adjacent the stitch-forming point, the work being clamped by means of a presser 15 against said work-table or support while stitch-forming operations are being performed, the pressure of the presser being relieved during the feeding action. In machines organized as heretofore the presser- 20 foot is automatically lifted from the adjoining surface of the work for and during the feeding action, but the work and work-table or support remain in contact with each other during the feeding action, so that the 25 advance of the work is resisted more or less by reason of such contact, thereby imposing increased strain upon the feeding implement. Consequently, this implement, being either the needle or the awl of the stitching instrumentalities, is subject to deflection 30 or bending, whereby the extent and uniformity of progress of the work in a feed movement are affected.

The general objects of the invention are 35 to provide against opposition by the work-table or support to the advancing movement of the work during the feeding action, and, through eliminating such opposition or resistance, thereby to facilitate the said movement and action, with other good results incident to relieving the work-penetrating feeding implement of strain due to resistance encountered in moving the work.

Briefly stated, the essential principle of the 40 invention consists in employing in a sewing machine, in conjunction with a work-penetrating and feeding implement, and with a movable presser engaging with one side of the work, and an automatic presser-lift, a 45 movable or reciprocating work-table or support for the other side of the work, and means for moving the work-table or support out of contact with the latter side of the work for and during the feed-movement so that as the feed-movement occurs the work 50 remains simply suspended upon the said im-

plement and is advanced without opposition resulting from contact with either the presser or the work-table or support.

An illustrative embodiment of the invention is shown in the drawings, in which latter,—

Fig. 1 is an elevation of certain portions of a sewing machine, including the said embodiment.

Fig. 2 is a view showing some of the parts of Fig. 1, looking from the left-hand side in Fig. 1.

Fig. 3 is a sectional view showing needle and awl carriers and certain associated parts.

Figs. 4, 5 and 6 are elevations illustrating the presser mechanism of Figs. 1 and 2, separately, and illustrating the working thereof.

Fig. 7 is a sectional detail.

The machine parts shown in the drawings include a machine-frame 1, Figs. 1 and 2, a cam-shaft 2, Fig. 1, a curved awl 3, Figs. 1 and 2, a swinging awl-carrier 31 and connections through which the awl-carrier and awl are actuated through the rotation of the cam-shaft, an awl-guard 4, a curved needle 5, a swinging needle-carrier 51, Fig. 3, (the actuating connections therefor being omitted in order to simplify the drawings), a needle-guard 6 that is partly shown in Fig. 3, and feed-mechanism which is referred to hereinafter briefly. Also, a presser 7, presser-locking and lifting mechanism to which reference is made later herein, a reciprocating work-table or support 8 and controlling and operating mechanism therefor to which also reference is made hereinafter, and certain other associated parts and devices.

A portion of work α is represented in certain of the views of the drawings, in place between the work-table or support 8 and the presser 7. As appears in the drawings, the awl 3 is arranged and actuated to penetrate from above the work α resting upon the work-table or support and at times clamped thereto by the presser, and the feeding of the work as successive stitches are made is accomplished by movement of the awl-carrier and awl in the direction of the feed while the awl is in the work.

The particular means and mode of mounting the awl-carrier and needle-carrier, awl-guard and needle-guard, actuating them for stitch-forming purposes, and occasioning the feed-movements of the awl-carrier and

awl, form no portion of the present invention and need only brief reference thereto. In the illustrated instance the awl-carrier 31 is fixed upon a rockshaft 311 carried by bearing-supports 312, 313, indicated in Figs. 2 and 3 but omitted from Fig. 1, the rockshaft having capacity for rocking movements to cause the awl to penetrate the work and afterward withdraw therefrom, and also having capacity for movement back and forth longitudinally for the purposes of the feed. To give the rocking movements to the rockshaft 311 so as to swing the awl-carrier and awl, the awl-carrier 31 is connected by a link 32 to an arm 33 of a rocker having its axis at 34 and having a second arm, 35, that is connected by a link 36 to an arm 37 of a second rocker having its axis at 38 and a second arm, 39, carrying a cam-follower 391 which works in a cam-groove 392 in a cam-hub 393 fixed to cam-shaft 2. As stated hereinbefore, the actuating mechanism for the needle-carrier and needle is not shown. In Fig. 3 the awl-guard 4 is sleeved upon the rock-shaft 311 with its sleeve 41 fitted to and extended through a bearing in the support 313, with a dished spring-washer 42 between the body of the awl-carrier and that of the awl-guard to act through friction to cause the latter to accompany the former in the movements of the former, and with a cap-screw 43 engaged with the adjacent outer end of the rockshaft with its flange contacting with the corresponding end of sleeve 41 so that by turning the said screw the spring-washer may be caused to act more or less effectively in causing the awl-guard to partake of the swinging movements of the awl-carrier. In Fig. 3, also, the needle-carrier 51 is shown as sleeved upon rockshaft 311, with its sleeve 52 extending through support 312, and the needle-guard 6 is shown as sleeved upon the exterior of said sleeve 52 of the needle-carrier, with the needle-guard sleeve 62 also extending through support 312 and fitting a bearing in said support within which it is adapted to turn. A dished spring-washer 63 is interposed between the body of the needle-carrier and that of the needle-guard to act through friction to cause the needle-guard to participate in the movements of the needle-carrier, and nuts 64, 64, applied to the screw-threaded outer end of needle-carrier sleeve 52 hold said sleeve and the needle-carrier from movement inward along rockshaft 311, while by adjustment of said nuts the tension of the spring-washer 63, and its efficiency in causing the needle-guard to participate in the swinging movements of the needle-carrier, may be varied. The feed-movements are transmitted to the rockshaft 311 through a feed-lever, 9, forming a part of the feed-mechanism and conveniently engaged with one end of said

rockshaft. For the purposes of the feed the rockshaft is moved endwise while the awl is in the work, advancing the work the distance of a stitch-length, the return movement of the rockshaft and awl taking place 70 while the awl is disengaged from the work. As the rockshaft moves endwise, it slides through the sleeve of the needle-carrier, which does not partake of the feed-movements, but the sleeve of the awl-guard slides 75 through the bearing within which it is fitted in support 313.

The presser-mechanism in connection with which the invention is utilized may vary in practice. In the present instance the presser-carrier 71 is mounted to rock upon an axis at 72, and for the purpose of moving the presser toward the work-table or support into a position determined by the thickness of the work resting upon the work-table or support; in other words, into a position determined by the upper surface of the said work, and causing the presser to cooperate with the work-table or support in clamping the work ⁸⁰ during the penetration of the work by the awl 3, etc., a spring 73 is combined with said presser-carrier. For the purpose of locking the presser in clamping position that is to say, in the said position determined by the thickness of the work, a pivoted locking dog 10 is employed to act in combination with a segment 101 carried by the presser-carrier, and a spring 102 is arranged to act normally upon the locking dog 10 so as to cause it to grip the segment 101 and prevent the presser from moving farther away from the work-table or support. Automatic release of the presser-grip or lock so as to leave the presser free to be lifted to provide for each feed-movement is effected by means of a release-cam 103, Figs. 5 and 7, fixed upon a rockshaft 11 mounted in the upper portion of the machine-frame. This rockshaft is rocked prior to each feed-movement, in this instance by means of an arm 111 fixed upon the rockshaft and connected by a link 112 to arm 37 of the rocker actuated by means of cam-groove 392. For the purpose of automatically lifting the presser after it has been unlocked, a lifting tappet 12 fixed upon the rockshaft 11 is employed in this instance to act in conjunction with a lifting-clamp arrangement carried by a movable arm 13 and adapted to engage with the segment 101 with which the presser-carrier is provided, as aforesaid. Arm 13 has a forked lower end that is engaged with a hub of the presser-carrier that is concentric with axis 72, so as to enable the arm to swing around the said axis. The drawings show a well-known lifting-clamp arrangement comprising a primary lever-member 121 with which lifting tappet 12 engages, a secondary lever-member 122 which is adapt- 85 90 95 100 105 110 115 120 125 130

ed to engage with the curved exterior surface of segment 101, and a strut 123 between the two levers and acting, when tappet 12 presses against primary lever-member 121, 5 to transmit movement to secondary lever-member 122 to cause it to grip upon the segment 101. In the working of the parts the tappet 12 acts through its pressure against primary lever-member 121 to close 10 the secondary lever-member 122 upon said segment, and then the continued pressure of the tappet against the primary lever-member operates to swing the arm 13 and presser-carrier, whereby the presser is lifted. As 15 tappet 12 swings in the reverse direction, the grip of secondary lever-member 122 upon segment 101 is relieved, and spring 73 thereupon acts to swing the presser-carrier so as to depress the presser. A spring 124, Fig. 1, 20 engaged with the upper portion of arm 13, returns such arm toward the axis of rock-shaft 11 when such return is permitted by the return movement of tappet 12.

To provide for manual unlocking of the presser in case such unlocking should become necessary, a second grip-release cam, 25 14, Figs. 2, 6 and 7, is mounted loosely upon rock-shaft 11 in position to act upon grip-lever 10, the said cam 14 having an arm 141, 30 Fig. 1, with which is engaged the upper end of a rod 15 which may be operated by the attendant as required. In practice the said rod usually is connected with a treadle. For the purpose of enabling the presser to be manually lifted, in addition to being manually unlocked as just explained, an arm 35 16, with which the rod 15 is connected also, is articulated with the presser-carrier by a pivotal joint at 161, the said arm having a finger 162 which projects down alongside the lower portion of the presser-carrier. The construction permits the automatic lifting and lowering of the presser to take place without being interfered with by the arm 40 16, but provides that as rod 15 is moved downward for the purpose of rocking the release-cam 14 in effecting manual unlocking of the presser the finger 162 shall make contact with the presser-carrier and rock the 45 50 same in the proper direction to lift the presser.

Having reference, now, to the reciprocating work-table or support,—

For the automatic movement of the work-table or support 8 downward from the under surface of the work, the said work-table or support is mounted upon a swinging-carrier 55 81, Fig. 1, which is mounted to swing about axis 72, the said carrier having an arm 82 which extends up into proximity to a cam 83 fixed upon a rockshaft 11. A spring 85, Fig. 1, engaged with said lever acts with a 60 tendency to draw the arm 82 toward the rockshaft and thereby depress the work-table or support. In the turning movement 65

of rockshaft 11 in one direction a high portion of cam 83 acting against arm 82 raises the work-table or support and holds the latter in elevated position, in effect locked in such position, during the penetration of 70 the work by the awl and the formation of a stitch, to provide for the backing-up, i. e., support, of the work against the thrust of the awl as such penetration is effected, and other stresses communicated to the work at 75 such time, and then in the reverse turning movement of the rockshaft a lower portion of the cam is presented to the said arm to permit the work-table or support to move away from the under surface of the work so 80 as to provide for the feed-movement.

In the action of clamping the work between presser-member 7 and work-table or support 8 after the presser under the impulse of the spring 73 has reached the upper surface of the work α and has been locked by grip-lever 10, the work-table or support 8 continues its upward movement toward presser-foot 7 and compresses positively the work between the lower face of presser-foot 90 7 and the upper surface of work-table or support 8. This permits of a positive clamping and avoids the necessity of using a very heavy spring at 73. This relieves the foot-lift mechanism from unnecessary labor in actuating presser-foot 7.

As a result of dropping the work-table or support simultaneously with the lifting of the presser, the work is left impaled upon the awl and supported by the engagement 100 with the blade or stem of the latter, without necessary contact of its surfaces with either the presser or the work-table or support during the advance of the work in the feed-movement of the awl.

What is claimed as the invention is:—

1. In a sewing machine, the combination with a work-penetrating and feeding implement, a presser movable toward and from the plane of the work engaging with one side of the work, an automatic presser-lift by which pressure of the presser upon the work is relieved at time of feed-movement, and a work-table or support for the other side of the work movable toward and from the plane of the work of means acting to move the work-table or support out of contact with the latter side of the work for and during the feed-movement so that as the latter occurs the work is advanced without necessary contact with either the presser or the work-table or support.

2. In a sewing machine, the combination with a work-penetrating and feeding implement, a presser movable toward and from the plane of the work and engaging with one side of the work, an automatic presser-lift by which pressure of the presser upon the work is relieved at time of feed-movement, and a work-table or support for the other

- 4 side of the work movable toward and from the plane of the work of a controlling cam for said work-table or support and means whereby said cam is actuated to provide for 5 the backing-up of the work during the penetrating action of said implement and for movement of the work-table or support away from the plane of the work to relieve the work from resistance due to the work-table or support during the feeding-action. 10
3. In a sewing machine, the combination comprising a work-penetrating and feeding implement, a work-support, a presser, means for moving said work-support and said presser, respectively, toward each other to clamp the work and hold it clamped during the penetration of the work by the said implement, and means for separating the work-support and the presser individually from 15 the respective surfaces of the work and out of contact with both of said surfaces during the feed-movement of the said implement and the work. 20
4. A sewing machine comprising in combination with a presser-foot, means for automatically locking and releasing same in position determined by thickness of work, means for automatically lifting said presser-foot from the adjacent surface of work, and a 25 work-compressing work-support which reciprocates toward and from the plane of the work. 30
5. A sewing machine comprising in combination with a presser-foot, means for automatically locking and releasing same in position determined by thickness of work, means for automatically lifting said presser-foot from the upper surface of the work each 35 time, and a work-compressing work-support 40 which reciprocates toward and from the plane of the work, positively locked in normal working position. 6. A sewing machine comprising, in combination, a presser-foot which reciprocates toward and from the plane of the work and is locked in engagement with the work, and a work-support which likewise reciprocates toward and from the plane of the work and is locked in engagement with the work. 45
7. A sewing machine comprising, in combination, a presser-foot, means for locking it in position determined by one surface of the work, and means for automatically lifting it from such surface, and a work-compressing work-support which reciprocates toward and 50 from the plane of the work. 55
8. A sewing machine comprising, in combination, a presser-foot, means for locking it in position determined by one surface of the work, means for automatically lifting it from such surface, a work-compressing work-support which reciprocates toward and from the plane of the work, and means for locking it in normal work-supporting position. 60
9. A sewing machine comprising in combination with a work-penetrating and feeding implement, a presser-foot, devices for automatically locking the presser-foot in position determined by thickness of work and releasing the same, and means for automatically lifting said presser-foot from the adjacent surface of the work for each feed-movement, a work-support, and means acting to move the work-support against the other surface of the work to co-act with the 65 presser-foot in compressing the work, and to move the work-support out of contact with such surface for and during the feed-movement. 70
